(57) **CLAIM**

(21) Appl. No.: **29/207,354**

The ornamental designs for electrode for a plasma arc torch, as shown and described.

(22) Filed: **Jun. 12, 2004**

DESCRIPTION

(63) Continuation-in-part of application No. 29/189,693, filed on Sep. 9, 2003, now Pat. No. Des. 496,376.

FIG. 1 is a perspective view of an electrode for a plasma arc

(51) **LOC (8) Cl.** **15-09**

FIG. 2 is a front elevation view thereof;

(52) **U.S. Cl.** **D15/144**

FIG. 3 is a top plan view thereof;

(58) **Field of Classification Search** D15/144,

FIG. 4 is a left end elevation view thereof;

D15/144.1, 144.2; 219/121.44, 121.5

FIG. 5 is a right end elevation view thereof;

See application file for complete search history.

FIG. 6 is a bottom plan view thereof; and,

(56) **References Cited**

FIG. 7 is a rear elevation view thereof.
